UNITED STATES PATENT OFFICE

GEORGE HENRY WHEARY, OF RACINE, WISCONSIN, ASSIGNOR TO WHEARY TRUNK COMPANY, OF RACINE, WISCONSIN, A CORPORATION OF WISCONSIN

LOCKING DEVICE FOR DRAWER SECTIONS

Application filed September 14, 1923. Serial No. 662,634.

This invention relates to certain new and useful improvements in locking devices for drawer sections and refers more particularly to a device of this character especially adapted for use in locking the drawers of a wardrobe trunk:

Wardrobe trunk drawer locking devices may be generally classified as the removable type which is in the form of a locking bar adapted to be secured across the fronts of the drawers, or the non-removable type which is actuated by one of the drawers to lock the others in closed position, and it is to this latter type that this invention relates.

Drawer locking devices of the last mentioned type have been open to several objections among which may be listed the cost incidental to their manufacture and installation, the unsatisfactory security offered against unauthorized opening of the drawers, and the inability to easily operate the same.

Having the above in mind this invention has for a primary object to provide locking means for the drawers of a wardrobe trunk of the character described, which may be easily and cheaply constructed and installed, is sturdy and prevents the unauthorized opening of the drawers and is readily actuated with a minimum effort.

This invention has for another object to provide a locking device of the character described which is concealed by the fittings of the trunk to in no wise mar the general appearance thereof.

It is a further object of this invention to provide an aligning strip and reinforcing member for the drawer section which is longitudinally channeled to form a guideway for reciprocally mounting and concealing a locking bar adapted, upon the closing movement of one drawer, to secure the others in closed position.

And a still further object of this invention resides in the provision of an improved reinforcing strip for the drawer section of a wardrobe trunk having means for housing and concealing a drawer locking device having a part engageable with a part carried by one

of the drawers when closed to lock the remaining drawers.

With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawings, I have illustrated one complete example of the physical embodiment of my invention constructed according to the best mode I have so far devised for the practical application of the principles thereof, and in which:

Figure 1 is a perspective view of a wardrobe trunk equipped with a drawer locking device embodying my invention, the sections being opened and several of the drawers removed;

Figure 2 is a fragmentary detail view, partly in section and partly in elevation, taken through Figure 3 on the plane of the line 2-2;

Figure 3 is a detail view looking on the plane of the line 3-3 of Figure 2, parts thereof being broken away and in section to illustrate details of construction;

Figure 4 is a view of one side of the wardrobe section of a trunk equipped with my invention, said view being taken on the plane of the line 4-4 of Figure 3 and having parts broken away and in section;

Figure 5 is a fragmentary detail view, partly in elevation and partly in vertical section, of a slightly modified form of my invention and illustrating the master drawer as in closed position to actuate the drawer locking device;

Figure 6 is a view, partly in section and partly in elevation, taken through Figure 5 on the plane of the line 6-6, and

Figure 7 is a fragmentary perspective view of one of the locking bars and illustrating one manner of forming the locking lugs thereon.

Referring now more particularly to the accompanying drawings, the numeral 10 des-

ignates the wardrobe section or compartment of a wardrobe trunk, and 11 the drawer section or compartment in which a plurality of drawers 12 are slidably mounted on angle irons or guides 13 secured to the opposite side walls or panels 14 of the drawer section. The wardrobe and drawer sections are connected in any ordinary or desired manner and are adapted to be locked in closed position by any suitable means, such means being illustrated in the present embodiment as a lock 15 carried by a hinged top section 16 hingedly connected with the drawer section and adapted to close over the top of the wardrobe section.

Externally secured to the side walls or panels 14 of the drawer section, and projecting beyond the margin thereof, is a metallic strip 17 which provides a valance adapted to close the line of juncture between the sections 10 and 11 when the trunk is closed. Internally secured to the side panels or walls 14 adjacent their margin is a strip 18 bent to the peculiar cross-section illustrated in Figure 2. Each strip 18 has its forward edge preferably bent over the margin of the adjacent trunk panel 14, as at 19, then extends inwardly along the inner wall of the panel a slight distance, as at 20, then directed inwardly at substantially right angles and then folded upon itself to provide a rib or flange 21, for the purpose hereinafter described, and then directed inwardly along the inner wall of the panel and medially provided with a longitudinal channeled portion 22, extending throughout substantially the entire length of the strip. The parts 23 on opposite sides of the channel 22 provide attaching flanges through which rivets or other securing means 24 are passed to secure the strip to the trunk side panel.

The ribs or flanges 21 of the strips 18 provide stops for the drawers 12 to prevent their movement into the section 11 inwardly of a line substantially flush with the outer margin of the panels 14. Each drawer has the forward corners of its bottom and side walls protected by a strip 25 providing a laterally projecting flange or rib 26 of substantially the width of the rib or flange 21 and of the approximate thickness of the section 20 of the strips 18 which abut the ribs 21 when the drawer is closed, see Figure 2.

Vertically slidably mounted in channel 22 of each strip 18 is a locking bar 27 provided at intervals, substantially equal to the width of the height of the drawers 12, with laterally projecting locking lugs 28 illustrated in the present embodiment as struck or stamped from the body of the bar, see Figure 7. The locking lugs 28 extend outwardly of the channel 22 through openings 29 therein and are engageable in front of keeper or receiver lugs 30 secured to the adjacent side walls of the

drawers 12, when the bar is depressed by the means to be hereinafter described.

The lower portion of each strip 18 has its channel 22 bulged or struck outwardly, as at 31, to form a pocket or casing for an expandable spring 32, the lower end of which engages against an instruck lug or finger 33 and the upper end of which engages against the lower end 34 of the bar 27 to thus normally, yieldably urge the bar upwardly to position the locking lugs 28 out of the path of the keepers or receivers 30 of the drawers. The locking bar is actuated against the force of spring 32 by one of the drawers, preferably the upper-most one, which is provided with a master-lock, not shown, to thus permit its securement in closed position independent of the other drawers.

In Figures 1 to 4, inclusive, the upper-most or master drawer actuates the locking bars by the side flanges or ribs 26 thereof engaging the outer free ends 35 of bell crank levers 36 pivotally secured at the outer ends of their other arms to bracket members 37, as at 41. One member 37 is secured to each side wall or panel 14 adjacent the top of the trunk and close to the strips 18 by rivets, screws or other members 38. The rib 21 and channel 22 of each strip 18 are preferably cut away adjacent the bell crank lever 36 and said lever is provided with an elongated aperture or opening 39 adjacent its apex, through which a pivot 40 carried by the upper end of the adjacent bar 27 passes. With this arrangement, an inward pressure on the outer free end of the arm 35 will cause a downward movement of the bell crank lever on its pivot 41 and consequently move the bar 27 connected therewith against the force of its spring 32, the elongated opening 39 accommodating for the variance in the distance between the pivots 40 and 41 as they are moved toward or away from a horizontally aligned position.

From this construction it will be obvious that as the upper-most or master drawer is moved toward closed position its side ribs or flanges 26 press against the outer free ends 35 of the bell crank lever 36 moving them on their pivots 41 to depress the locking bars against the action of their springs, positioning the locking lugs 28 in front of the keepers 30 of any drawer that may be in closed position to thus lock the same until the master drawer is moved toward open position to permit upward movement of the locking bars by the springs 32. The keeper lugs 30 preferably have their forward and rear surfaces tapered, as illustrated in Figure 3, so that should any one of the drawers be slightly opened, the closing action of the lugs 38 will not be interfered with.

In Figures 5 and 6 I have illustrated a slightly modified means for depressing the bars 27. In this form of my invention the bell crank levers are dispensed with and up-

per ends of the locking bars bent laterally, as at 42, through opening 43 in the channels to normally lie in the path of inclined angle plates 44 secured to the sides of the master drawer 12. With this construction, closing movement of the master drawer causes the inner ends of the angle members 44 to ride over the instruck locking bar ends 42 to depress the bars 27 as will be readily obvious and engage the lugs 28 in front of the receiver lugs 30 or else in the recesses or notches 45 in the drawer side walls as illustrated in the modification depicted in Figure 5.

From the foregoing description taken in connection with the accompanying drawings, it will be readily obvious to those skilled in the art to which an invention of this character appertains that I provide an improved drawer locking device of the character described which may be readily applied to wardrobe trunks without increasing the cost thereof, may be made for any size trunk, inasmuch as the strips 18 may be provided with openings 29 so arranged as to be adaptable for either five, six or any other number of drawers only necessitating the provision of locking bars 27 having the required number of locking lugs 28.

What I claim as my invention is:

1. In a device of the character described having a drawer section and drawers slidably mounted therein for opening and closing movement, a reinforcing strip secured to one drawer section panel adjacent its marginal edge, said reinforcing strip having a longitudinally extending channel therein to provide a guide, a bar mounted in said channel and guided by the walls of the channel and said panel for longitudinal movement, locking lugs connected with said bar and exposed outwardly of said reinforcing strip, keepers carried by the drawers adjacent said lugs, and means operable by the closing action of one of the drawers to actuate said bar and engage said locking lugs with the drawer keepers to secure the drawers in closed position.

2. In a device of the character described having a drawer section and drawers slidably mounted therein for opening and closing movement, a bar mounted in the drawer section, locking lugs connected with said bar, keepers carried by the drawers adjacent said locking lugs, a flange projecting laterally from the front face of one drawer for limiting the closing movement of said drawer, and means connected with said bar and engageable by said drawer flange as said drawer closes to engage the locking lugs with the keepers of the other drawers and secure the drawers in closed position.

3. In a device of the character described having a drawer section and drawers slidably mounted therein for opening and closing movement, a bar longitudinally shiftably

mounted in the drawer section, means preventing sidewise movement of said bar, locking lugs connected with said bar, keepers carried by the drawers adjacent said locking lugs, a bell crank lever, means pivotally securing the end of one arm of said lever to the drawer section, an elongated opening in the bell crank lever adjacent its apex, a pivot pin carried by the lever and engaging in said elongated opening whereby movement of the bell crank lever on its pivot longitudinally shifts said bar to engage the locking lugs with the drawer carried keepers, means carried by one of the drawers and adapted upon closing to engage the free end of the other arm of said lever to move the lever on its pivot, and spring means normally urging said bar to a position free of the locking lugs of said keepers to permit unrestricted opening and closing of the drawers.

4. In a wardrobe trunk, the combination with a drawer compartment including a side panel, of a finishing strip formed of bendable metal and extending along the margin of said panel, a vertically extending shoulder formed in the strip to provide a drawer stop, a drawer locking bar, and a guide-way longitudinally formed in said strip to provide means for concealably mounting said drawer locking bar.

5. In a wardrobe trunk, the combination with a drawer compartment including a side panel, of a finishing strip extending along the margin of said panel, a vertically extending shoulder carried by the strip to provide a drawer stop, a drawer locking bar, a guide-way longitudinally formed in said strip to provide means for concealably mounting said drawer locking bar, a spring normally urging said bar upwardly, and an out-struck portion formed in said guide-way to provide a housing for said spring.

6. In a device of the character described having a drawer section and drawers slidably mounted therein for opening and closing movement, a reinforcing strip secured to the drawer section adjacent its marginal edge, said reinforcing strip having a longitudinally extending channel therein to provide a guide, a bar mounted in said channel and guided thereby for longitudinal shifting movement, locking lugs connected with said bar and exposed outwardly of said reinforcing strip, keepers carried by the drawers adjacent said lugs, operating means formed on the upper end of said locking bar, and means adapted to coact with the first said means carried by the adjacent side of the upper-most drawer and engageable with the first said means upon closing of said upper drawer to longitudinally shift the locking bar and engage said locking lugs with the drawer keepers.

7. In a wardrobe trunk, having a drawer section and drawers slidably mounted therein for opening and closing movements, a finish-

ing and reinforcing strip secured to the inner surface of one section side panel adjacent its outer marginal edge, a vertically extending shoulder carried by the finishing strip to co-operate with a lateral flange carried by the drawers to limit the movement of the drawers into the section, a vertical guide-way formed in the strip rearwardly of its stop, a bar slidably mounted in the guide-way and protected and concealed thereby, locking elements carried by the bar and projected outwardly of the finishing strip to engage with drawer carried means when the bar is in one position to lock the drawers against movement outwardly of the section, means connected with the bar exteriorly of the finishing strip and normally extended beyond the stop thereof to be engaged by the flange of one drawer as it closes to actuate said means and move the bar with its locking elements to lock the other drawers closed.

8. In a device of the character described, the combination of a drawer section and a plurality of drawers movable therein, a facing strip secured to the inner edges of the drawer section and provided with a flange against which drawers abut when in a closed position, said strip having formed therein a channel for the reception of a movable drawer locking element, said element provided with an operating extension projecting through said flange, and said extension being actuated upon the closing movement of one of the drawers.

33 85 In testimony whereof I affix my signature.
GEORGE HENRY WHEARY.
